(57) **CLAIM**

The ornamental design for a kitchen appliance with a mixing attachment, as shown and described.

DESCRIPTION

FIG. 1 is a left side, front, top perspective view showing the kitchen appliance with a mixing attachment, the broken line showing of display elements and the mixer within the attachment are for illustrative purposes only and form no part of the claimed design;

FIG. 2 is a left side, front, top perspective view showing the kitchen appliance with no attachment for ease of illustration, the broken line showing of the display elements are for illustrative purposes only and form no part of the claimed design; and,

FIG. 3 is an enlarged partial front perspective view showing the kitchen appliance with no attachments, the display elements, which are shown in phantom, do not form part of the invention.

The underside of the kitchen appliance is plain and unornamented. The underside of the attachment is designed to fit snugly on top of the kitchen appliance and is plain and unornamented.
